CHARLES ADDISON MACDONALD AND MARTIN P. DOUGHERTY, OF ROCHESTER, NEW YORK, ASSIGNORS, BY DIRECT AND MESNE ASSIGNMENTS, OF ONE-HALF TO CHARLES J. PEMBROKE AND ONE-HALF TO FRANK KEIPER, BOTH OF ROCHESTER, NEW YORK.

PRESS-GUARD.

1,314,750.

Specification of Letters Patent. Patented Sept. 2, 1919.

Application filed August 17, 1916. Serial No. 115,520.

To all whom it may concern:

Be it known that we, CHARLES A. MACDONALD and MARTIN P. DOUGHERTY, of Rochester, in the county of Monroe and State 5 of New York, have invented certain new and useful Improvements in Press-Guards; and we do hereby declare the following to be a full, clear, and exact description of the same, reference being had to the accompanying 10 drawings, forming part of this specification, and to the reference-numerals marked thereon.

Our present invention relates to safety appliances for machinery, and it has for its 15 object to provide a simple, convenient and efficient guard for punch presses and the like, that will be sure in its operation, and will offer an infallible preventive to the insertion of the hand of the operative into the 20 dangerous region of the press when the ram or equivalent part is descending. The improvements are directed toward perfecting the reliability of the apparatus through automatic actuations performed by the ram 25 itself, if need be, and to accomplishing this object while still retaining a certain latitude in operating the press under circumstances wherein the safety appliance or guard can best be momentarily dispensed with. To 30 these and other ends the invention consists in certain improvements and combinations of parts, all as will be hereinafter more fully described, the novel features being pointed out in the claims at the end of the specification.

In the drawings:

Figure 1 is a front elevation of the upper portion of a punch press provided with a safety appliance constructed in accordance 40 with and illustrating one embodiment of our invention;

Fig. 2 is a side elevation of the press and guard;

Fig. 3 is a reduced front elevation of the 45 safety appliance with the guard in operative position;

Fig. 4 is a horizontal section taken substantially on the line 4—4 of Fig. 1, and

Fig. 5 is a detail section taken substantially on the line 5—5 of Fig. 1.

Similar reference numerals in the several figures indicate the same parts.

In the present embodiment of the invention, the guard is of the type which swings 55 back and forth in a vertical plane in front

of a vertical ram to knock the arms and hands of the operator laterally out of the way when the ram descends. There are two ways of operating such a guard, one of which consists in connecting it up with the clutch 60 treadle of the press so that it will move to operative position as soon as the clutch, that causes the descent of the ram, is thrown in, and the other consists in connecting up the guard to be moved by the ram itself during 65 the initial part of its down stroke. By the first of these methods, the movement of the guard, while rapid, is not so abrupt as to result in an unduly harsh contact with a man's arm in case it is in the way, but also this 70 method does not result in an infallible safety appliance, as, for instance, the clutch may stick, causing a repetition of the movement of the ram with one actuation of the treadle. The guard being released and the ram being 75 on the reverse stroke, the operator has no reason to expect that it will immediately descend again before he again presses the treadle, and it is in just such an emergency that an accident is apt to occur. On the 80 other hand, the operation of the guard by the ram itself during the down stroke, while sure, is abrupt, particularly with a quick acting press, so that the operator is exposed to unnecessary roughness in the forcible 85 ejection of his arm or hand when in the danger zone.

In the practice of our present invention, we retain the desirable features of both methods while eliminating the undesirable 90 features, by operating the same guard arm by means of the clutch treadle in ordinary running when everything is acting properly, and by the ram itself in case of an emergency, where the clutch sticks, or for other 95 reasons the ram repeats its descent without an inadvertent actuation of the treadle by the operator. We also provide means whereby the guard is locked operative position while the ram is down, and is released by the latter on the return stroke unless it is desired to voluntarily release it for certain purposes.

Referring more particularly to the drawings, and to Figs. 1 and 2 thereof, the press to which our appliance is shown attached comprises a frame 1 above a bed 2, in which frame a ram 3 is guided at 4 to reciprocate vertically on the crank 5 of a shaft 6. 7 indicates a male die carried by the ram as it moves toward and from the 110

bed 2 to coöperate with a female die 8 on the latter, 9 being the die clamp. The shaft 6 is rotated by a drive wheel 10 through the medium of a clutch 11 which, when actuated, 5 causes the ram 3 to make one reciprocation, namely, to approach the bed 2 and return to the elevated position shown in Fig. 1. The clutch is actuated (Fig. 2) by a pull rod 12 connected to a lever 13 pivoted at 14 at the 10 side of the frame 1. A link 15 is connected to the lever 13 and to a lever 16, which latter is in turn connected by a link 17 to a foot treadle 18 pivoted at 19 to the base frame 20 of the machine. The foot treadle 18 is normally held raised by a spring 21, and when depressed it rocks the lever 13 downwardly, 15 as is clear from an inspection of Fig. 2.

The safety appliance is carried by a bridge 22 supported on brackets 23 at each 20 side of the upper frame 1, which bridge piece spans the ram 3 and its guides. A guard arm 24 is pivoted centrally of the bridge 22 at 25 to vibrate toward the right from the inoperative position of Fig. 1 in 25 a vertical plane. A vane or shield 26 carried at the lower end of the arm assumes the position shown in Fig. 3 when the guard is operated and obstructs access from the front to the dangerous region between the dies 30 7 and 8 on the ram and bed respectively. In moving to this operative position, the guard will thrust the arm or hand of the operator aside if it is in the danger zone, and to prevent bruising the flesh the vane or arm 35 is preferably provided with a rubber or other pad 27 at the right or advancing edge. The arm or lever 24 is pivoted to a link 28 proceeding to the right therefrom at its upper end above the pivot 25. Pivoted to 40 the link at 29 is the lower arm of a lever 30 pivoted at 31 to the bridge 22 to vibrate in a plane parallel with that of the guard lever 24, and the lever 30 is in turn pivoted at 32 on its upper arm to a vertical link 45 33 having an adjustable slot and pin connection at 34 with the forward end of lever 13. From this it will be seen that as the lever 13 is drawn downwardly by the foot treadle 18 in actuating the clutch 11 to cause 50 a reciprocation of the ram 3, the guard arm 24 and shield 26 will be rocked from the normal position of Figs. 1 and 2 to the operative position of Fig. 3, in front of the dies 7 and 8, and in doing so will throw out the operator's hand, if in the way, previous to the descent of the ram. The clutch 11 is not thrown in immediately upon the initial movement of the lever 13, but the guard is immediately moved, so that the 55 guard reaches operative position before the ram descends, the clutch taking its grip only during the last fractional part of the movement of the treadle and lever 13. Being manually operated, the guard moves quickly 60 but rather gently to position, and the opera-

tor suffers no discomfort from having his hand brushed aside thereby.

Should this manual operation of the guard fail for any reason whatever, the guard will still come to operative position 70 through another operating connection. Referring more particularly to Figs. 1 and 4, the pivot hub 35 of the guard arm 24 is provided with a crank arm 36, carrying an inwardly projecting roller 37. When the 75 guard is in inoperative position, as in Fig. 1, this roller lies in the path of an L-shaped abutment 38, mounted for vertical adjustment on the ram 3 by bolts 39 extending through a slot 40 therein. The offset of 80 the crank arm 36 is such that, during the first part of the movement of the ram, it will be engaged by the abutment 38 and carried far enough to rock the guard arm 24 to operative position before the dies 7 and 85 8 have come close enough together to work injury to the hand of the operator, if lying between them. As before explained, the guard moves under the influence of the foot treadle before there is any movement on the 90 part of the ram, so that if the foot treadle connection is working all right, the stop 38 does not engage the roller 37 at all, but the latter is moved in advance of it. Therefore, this automatic actuation of the guard 95 by the ram occurs only in an emergency, and in the event that the clutch 11 sticks, or for other reasons the ram repeats its descent independently of the treadle. There is hence no continuous noisy and wearing 100 battering of the guard mechanism by the ram during the normal operation of the press.

The spring 21 of the treadle, of course, has a tendency to return all of the connected parts, including the guard mechanism, but to reinforce its action and insure a prompt return of the guard arm 24 to inoperative position we prefer to connect a spring 41 with the lever 30 and with a fixed 105 part of the frame 1, such as the arm 42 on the bridge piece 22 (Fig. 1).

We prefer to also provide for locking the guard in operative position until the ram has proceeded upwardly again, away from 110 the bed, so that the guard cannot be brushed aside once it has reached its operative position. To this end, a small shaft 43 is journaled in ears 44 on the bridge piece 22, and carries fixed thereto a latch arm 45 and a trip finger 46. The latch arm 45 is normally yieldingly held by a spring 47, tending to rotate the shaft 43 to a position in which it will automatically engage with a notch 48 in the link 28 of guard arm 24 when 115 the latter is rocked sufficiently and lock it in operative position. As before stated, with the foot treadle actuation of the guard, this will occur before the ram starts its descent, and a trip 49 (Fig. 5) carried by the 120

- ram on the abutment 38, in descending later, passes the trip finger 46 because of the yielding of a cam pin 50 on the latter having a spring 51 behind it. When the ram moves 5 upwardly again, however, the trip 49 engages the under side of the pin 50, which latter does not then yield, and the trip finger 46 is rocked upwardly, rotating the shaft 43 and carrying the latch arm 45 against 10 the tension of spring 47, out of locking engagement with the notch 48 on the link 28 of guard arm 24, permitting the latter to be withdrawn to inoperative position by its spring 41.
- 15 If, in the preliminary adjustment of the dies, for instance, it is desired to have access to them while the dies are in contact, or very near it, the latch 45 is free to be released by hand, but of course the stop 38 20 must be taken off or first adjusted to its

upward extreme in order not to confine the movement of the crank 36 and roller 37.

We claim as our invention:

In a safety device for a punch press, the combination of a bridge, a vertically disposed guard pivoted to said bridge, a crank, a link connecting said crank to the guard, means for rocking said crank from the treadle and thereby rocking said guard through said link, a crank extending laterally from 25 said guard, and a horizontal abutment carried on the ram of the press which makes contact with said crank for the purpose of rocking it and moving the guard as the ram descends.
